Primary Examiner—Antoine Duval Davis*Attorney, Agent, or Firm*—Charles W. Alworth; Ronald B. Sefrina[57] **CLAIM**

The ornamental design for a molded utility meter lens with a bolt hole pattern lip, as shown and described.

DESCRIPTION

FIG. 1 is a top plane view side of the molded utility meter lens with a bolt hole pattern lip showing my new design;

FIG. 2 is a side elevational view of the molded utility meter lens with a bolt hole pattern lip;

FIG. 3 is a side elevational view of the molded utility meter lens with a bolt hole pattern lip rotated by ninety degrees from the view in FIG. 2, further showing my new design; and,

FIG. 4 is a bottom plan view of the molded utility meter lens with a bolt hole pattern lip.

My new molded utility meter lens with a bolt hole pattern lip is preferably manufactured from clear plastic so that the internals of the meter may be seen. The bolt hole pattern lip fits perfectly upon the corresponding lip of the utility meter in which the design is to be placed.
